CLAIM

The ornamental design for a support strap dispenser, as shown and described.

DESCRIPTION

FIG. 1 illustrates a front isometric view of the support strap dispenser in a closed position without showing a roll of the support strap;

FIG. 2 illustrates a rear isometric view thereof;

FIG. 3 illustrates a front elevation view thereof;

FIG. 4 illustrates a rear elevation view thereof;

FIG. 5 illustrates a top plan view thereof;

FIG. 6 illustrates a bottom view thereof;

FIG. 7 illustrates a left-side elevation view thereof;

FIG. 8 illustrates a right-side elevation view thereof;

FIG. 9 illustrates a front isometric view of the support strap dispenser in an open position without showing a roll of the support strap;

FIG. 10 illustrates a rear isometric view of FIG. 9;

FIG. 11 illustrates a front elevation view of FIG. 9;

FIG. 12 illustrates a rear elevation view of FIG. 9;

FIG. 13 illustrates a top plan view of FIG. 9;

FIG. 14 illustrates a bottom view of FIG. 9;

FIG. 15 illustrates a left-side elevation view of FIG. 9;

FIG. 16 illustrates a right-side elevation view of FIG. 9; and, FIG. 17 illustrates a front isometric view of the support strap dispenser in a closed position and comprising a roll of the support strap.

In FIG. 17, the broken lines represent unclaimed environmental subject matter and do not form part of the claimed design.
